His Attorney.

UNITED STATES PATENT OFFICE.

WILLIAM L. R. EMMET, OF SCHENECTADY, NEW YORK, ASSIGNOR TO GENERAL ELECTRIC COMPANY, A CORPORATION OF NEW YORK

ELECTRIC SHIP PROPULSION.

1,290,945.

Specification of Letters Patent. Patented Jan. 14, 1919.

Application filed July 8, 1915. Serial No. 38,807.

To all whom it may concern:

Be it known that I, WILLIAM L. R. EMMET, a citizen of the United States, residing at Schenectady, county of Schenectady, 5 State of New York, have invented certain new and useful Improvements in Electric Ship Propulsion, of which the following is a specification.

My invention relates to electric ship propulsion and in particular to the propulsion of ships by alternating current induction motors. The object of my invention is to provide a novel and improved arrangement of apparatus for operating ships with a 10 minimum of apparatus. A further object of my invention is to provide improved apparatus for operating an electrically propelled ship at full and maneuvering speeds in a more simple, satisfactory and efficient 15 manner than has heretofore been done. Other objects of my invention will be apparent from the following description and appended claims.

The features which I believe to be patentably characteristic of my invention are definitely indicated in the claims appended hereto. The methods of operating an electrically propelled ship and the novel and improved arrangements of apparatus for 20 carrying out these methods, in accordance with my present invention, will be understood from the following description taken in connection with the accompanying drawings in which:

Figure 1 illustrates diagrammatically a system of electric ship propulsion embodying the features of my present invention; Fig. 2 is a detail view of the secondary winding of the motor shown in the system of Fig. 35 1; and Fig. 3 is a detail view of a modified type of secondary winding.

A system of ship propulsion generally consists of three elements—(1) a main motive means or prime-mover, such as a steam engine or elastic fluid turbine, (2) a propeller shaft and (3) a speed reducing mechanism for securing the desired speed ratios between the prime-mover and the propeller shaft. In an electrically propelled ship, the 45 speed reducing mechanism takes the form of an electric generator driven by the prime mover and supplying electric energy to an electric motor connected to the propeller shaft. The use of alternating current is 50 very desirable in electrically propelled ships,

since alternating current generators and motors are simpler than corresponding direct current machines, and the generators can be conveniently designed for larger capacities and higher speeds, and are, therefore, better adapted for use with steam turbines. Alternating current induction motors are also desirable, since they can be constructed and wound to withstand the roughest usage 60 with a minimum amount of trouble and expense for maintenance.

A ship is usually run at one particular speed during the greater part of the time its propelling apparatus is in use, and in most cases it is only when maneuvering in harbors or about wharves that different speeds are used. The power required to drive a ship 70 varies substantially as the cube of the ship's speed. The maximum power required for running at full speed ahead is, therefore, 75 very considerably greater than the power required for lower navigating speeds. The resistance offered by the water to a propeller is substantially constant for any particular speed of the ship, and, accordingly, the 80 power required to drive the ship is substantially constant for any particular ship's speed. The normal starting of the ship in either direction from a condition of rest does not require much power or the application 85 of a relatively large torque, since the speed, and hence the required power, increase gradually from their respective initial or minimum values. Where alternating current is used, starting can be very effectively 90 accomplished by bringing the propeller-driving motors and the alternating current generator up to speed together. Thus, little or no difficulty is ordinarily encountered in bringing a ship from stand-still up to and 95 in maintaining cruising or full running speeds ahead. In maneuvering and particularly in reversing very exacting and abnormal demands are made upon the propelling apparatus. For example, where a ship must 100 be suddenly reversed, or even stopped, when running at full speed ahead, a very large reversing torque must be available. And again, in maneuvering in harbors and around wharves a large torque is frequently required 105 for quickly reversing the direction of motion of the ship. The most exacting and difficult maneuver is obviously the reversal, or even the stopping, of the ship after full speed

If a ship is running at full speed ahead 110

and the application of power to a propeller shaft is stopped, the propeller will continue to spin around in the reverse direction, due to the motion of the ship. In order to reverse the direction of rotation of the propeller, a torque must be applied to its shaft sufficiently great to break the propeller away from the water. If the reversing torque is not large enough to break the propeller away from the water, the propeller will merely continue to spin around in response to the motion of the ship, while the ship will slow down very gradually, and the propeller will not break away from the water until the torque, due to the motion of the ship, becomes smaller than the reversing torque. When once the propeller has been broken away from the water, its reversal apparently becomes easier, and the ship can then be brought to rest and started in the reverse direction. Thus, a very high speed of the propellers in the reverse direction is not practicable until the ship has been brought to rest and given a high speed in the reverse direction, so that the real need of reversing is not the ability to produce high propeller speed, but the ability to produce high torque with a reduced propeller speed.

30 The torque of an induction motor for a given generator output is increased by increasing the number of primary poles, since increasing the pole number of the primary winding of the motor corresponds to increasing the speed reduction between the prime-mover and the propeller shaft. The torque of an induction motor may also be increased by increasing the resistance losses in the secondary winding, but since high torque so obtained means large secondary losses, efficiency must generally be sacrificed where high torque is desired. For running a ship at full speed ahead the maximum power is required, and it is essential that the propeller-driving motors should then operate at high efficiency. The maneuvering operations of a ship last for relatively very short intervals of time, and it is not required that the propelling apparatus be economically operated during these brief intervals. It will thus be seen that efficiency may well be sacrificed to secure high torque during the brief intervals of maneuvering, provided the propeller-driving motors operate with high efficiency at full speed. My present invention contemplates the provision of a novel and improved method of and apparatus for operating an electrically propelled ship with high efficiency at full running speeds ahead and with high torque for reversing the direction of motion of the ship.

65 My present system of propulsion comprises a suitably driven alternating current generator supplying energy to an induction

motor having its rotor mounted on the propeller shaft. As is well known, the speed ratio between such a generator and motor can be changed by changing the number of poles of the primary winding of the motor. The induction motor of my present system has a primary winding, or windings, adapted to produce magnetic fields of two different pole numbers, and in its preferred form is provided with means whereby an increased torque is produced when the primary winding is arranged for reversing. This increased torque can be produced by employing a secondary winding affording a low resistance path for the secondary current for the high speed pole number and a relatively high resistance path for the low speed pole number. Numerous constructions and arrangements of secondary windings possessing such characteristics will suggest themselves to those skilled in the art, such for example as a secondary winding so connected to an external resistance that the resistance is inactive for the high speed pole number and active for the low speed pole number, or a secondary winding of which one component is of low resistance and the other of relatively high resistance, the low resistance component being in effect substantially open-circuited for the low speed pole number. An increased torque for reversing may also be obtained by using an induction motor designed to have a secondary circuit of relatively high effective resistance at large slips of the motor. In the broadest aspect of my invention, pole-changing alone may be employed for reversing. My method of operating this system consists in connecting the primary winding for its high speed pole number for running the ship at full speed ahead and for its low speed pole number for reversing the direction of motion of the ship.

I am aware that pole-changing has heretofore been used to obtain different speeds of an induction motor, but I believe I am the first to employ pole-changing in a system of electric ship propulsion for the purpose of obtaining an increased motor torque for reversing the direction of motion of the ship. As previously explained, the torque of an induction motor, for a given generator output, is increased by increasing the number of primary poles because the motor speed is thereby decreased. This will be understood by remembering that the generator and motor act as a speed reducing mechanism between the prime-mover and the propeller shaft. In accordance with my present method of operation, the generator output is, for the purpose of reversal, utilized at a lower propeller speed, whereby the propeller-driving torque is increased.

Referring now to Fig. 1 of the drawings,

there is diagrammatically represented an elastic fluid turbine 10 mechanically coupled to a polyphase alternator. I have shown for the purpose of illustration an alternator of 5 the revolving field type having an exciting winding 11 supplied with direct current from any suitable source 12 by means of slip rings 13 and coöperating brushes. The alternator has a polyphase stator winding 14 10 connected to bus bars 15 or the like. The propeller 16 is mounted on the same shaft 17 as the rotor 18 of an induction motor. In the drawings, I have illustrated the secondary winding of the motor as carried by the 15 rotor member and the primary winding as mounted in the stator member, but it will of course be understood that the primary winding may be carried by the rotor member, in which case, the secondary winding will be 20 incorporated in the stator member.

The primary winding 20 of the motor is adapted to be arranged for a plurality of different pole numbers. To this end any of the well known means for producing primary magnetic poles of different pole numbers may be employed, and since there are numerous arrangements for effecting this purpose I do not deem it necessary to explain in detail any specific means, but by way of 25 example, I will mention a patent of Ernst F. W. Alexanderson No. 841,609, dated January 15, 1907 as illustrating one way in which the primary winding 20 may be arranged to produce primary magnetic poles of different 30 pole numbers. For the purpose of explaining my invention, I have illustrated a pole-changing switch 21 connected to the primary winding 20 by six leads 22 and to the bus bars 15 by three leads 23. This diagrammatic representation of a primary winding adapted for pole-changing will be well understood by those skilled in the art. A reversing switch 24 is associated with the leads 23 and serves to reverse the phase rotation 35 between the magnetic field of the alternator and that of the motor in the well understood manner. A switch 25 is also provided for disconnecting the motor from the bus bars.

The pole-changing switch 21 changes the 40 speed ratio of the motor with respect to the frequency of the alternator. The relative values of these speed ratios will be determined by the particular conditions to be met, such as the desired full speed of the ship, 45 and the magnitude of the reversing torque required for such a ship. The higher speed ratio is employed for running the ship at full speed ahead while the lower speed ratio is employed for reversing the direction of 50 motion of the ship. I believe it will generally be found necessary to provide means for accentuating the motor torque for the lower speed ratio. This can be advantageously done by providing a secondary winding 55 which has low resistance for the high speed pole number and relatively high resistance for the low speed pole number of the primary winding. Merely for the purposes of explanation I have in the accompanying drawings illustrated a compound or 60 double secondary winding. One winding is made up of relatively high resistance conductor bars 25 connected at their ends to end rings 26 to form a squirrel cage winding of relatively high resistance. This winding 65 is obviously effective for any pole number of the primary winding. The other winding is a definite winding and consists of low resistance conductor bars 27 having end connectors 28 connecting the bars as a polar winding. The end connectors are so designed that the pitch of the conductor bars 27 is substantially 100 per cent. when the primary winding is arranged for its high speed pole 70 number and in the neighborhood of 200 per cent. when the primary winding is arranged for its low speed pole number. Thus, the conductor bars 27 form a low resistance path for the secondary current when the primary winding is arranged for the high speed ratio, and are substantially open-circuited when the primary winding is arranged for the low speed ratio. 75

The torque of the propeller driving induction motor may also be advantageously accentuated by employing a secondary winding of inductively changing effective resistance, that is to say a secondary winding whose effective resistance inductively changes, so that the effective resistance 80 varies as a direct function of the frequency of the secondary current. Such a winding has relatively high effective resistance when the secondary current is of high frequency and relatively low effective resistance when the secondary current is of low frequency. Numerous constructions and arrangements for obtaining a secondary winding having an inductively changing effective resistance 85 are known in the art, and I have, merely for the purposes of illustration, shown in Fig. 3 of the accompanying drawings a double squirrel cage winding. The conductor bars 90 95 of one of these squirrel cage windings are of low resistance and are positioned in slots well beneath the surface of the magnetic core of the rotor, and since these conductor bars are substantially embedded in magnetic material, the winding as a whole 100 has high inductance. The conductor bars 30 of the other squirrel cage winding have relatively high ohmic resistance and are located in slots near the surface of the magnetic core of the rotor, and, thus, this winding as a whole has little inductance. On account of its high self-induction, the low resistance winding carries very little current when the frequency of the secondary current is high, and consequently under this condition the secondary current is forced to flow 110 115 120 125 130

through the conductors 31 of the high resistance winding. As the frequency of the secondary current diminishes, more and more current flows through the low resistance winding, until at normal slip the motor has the desirable running characteristics of an induction motor with an ordinary squirrel cage secondary winding. In the act of reversal, the direction of rotation of the primary magnetic field of the propeller driving motor is reversed. At the instance of reversal, after full speed ahead, the slip of the motor is abnormally high, because the rotor is revolving in the opposite direction to the primary magnetic field, and the secondary current is hence of relatively high frequency, being in fact nearly double the frequency of the primary current. The secondary winding, therefore, has a relatively high effective resistance, which it retains until the ship has been reversed and the slip of the motor reaches its normally small value.

The arrangement of apparatus in accordance with my present invention is capable of giving an increased torque in reversing with lighter apparatus and better power factor under normal operating conditions than in any similar system with which I am acquainted. The propeller-driving motor in my present system has a secondary winding of low resistance when the motor is connected for running the ship at full speed ahead, and the efficiency of the motor for this condition of navigation will, accordingly, be high. When connections for reversal are made, the pole number of the primary winding is increased, thereby increasing the torque available with the generator output, and the secondary losses are simultaneously increased, due to the increased effective resistance of the secondary winding for reversing purposes whereby the required reversing torque is produced. The pole-changing arrangement and increased effective resistance of the secondary winding of the motor thus produces a satisfactory reversing torque with little or no distortion of the normal operating characteristics of the motor.

While I have shown a single motor connected to one propeller shaft, it will be obvious that a ship may, and usually will, have more than one propeller. My present invention is concerned with the arrangement of apparatus for operating a propeller driving induction motor, preferably possessing certain particular characteristics, whether or not such motor is used alone or in combination with the same or other forms of motors. I do not, therefore, wish to be restricted to the particular arrangement of apparatus herein illustrated and described for the purpose of explaining the principle of my invention, but I aim in the appended claims to

cover all modifications within the spirit and scope of my invention.

What I claim as new and desire to secure by Letters Patent of the United States, is:—

1. A system of electric ship propulsion comprising a propeller, an induction motor adapted to drive said propeller, said motor having a primary winding adapted to produce primary magnetic fields of different pole numbers, two secondary windings one of which serves as means for developing a motor torque for running the ship at full speed ahead when the primary winding is connected to produce a relatively low number of poles and the other as means for increasing the motor torque for reversing the direction of motion of the ship when the number of primary magnetic poles is increased, said secondary windings being connected and arranged so that the secondary resistance losses of the motor are increased when the number of primary magnetic poles is increased, and means for connecting said primary winding to produce the lower number of poles for normal continuous operation of the ship and for producing the higher number of poles when reversing the direction of motion of the ship.

2. A system of electric ship propulsion comprising a propeller, an induction motor adapted to drive said propeller, said motor having a primary winding adapted to produce primary magnetic fields of two different pole numbers and a secondary winding having one portion of relatively high effective resistance for the higher number of primary poles and another portion of low effective resistance for the lower number of primary poles, and means for connecting said primary winding to produce the lower number of poles for normal continuous operation of the ship and to produce the higher number of poles for reversing the direction of motion of the ship.

3. A system of electric ship propulsion comprising a propeller, an induction motor adapted to drive said propeller, said motor having a primary winding adapted to produce primary magnetic fields of two different pole numbers and two secondary windings one of which is a short circuited winding of relatively high resistance and the other a low resistance definite winding for the lower number of primary poles but virtually open-circuited for the higher number of primary poles, and means for connecting said primary winding to produce the lower number of poles for normal continuous operation of the ship and to produce the higher number of poles for reversing the direction of motion of the ship.

4. A system of electric ship propulsion comprising a propeller, an induction motor adapted to drive said propeller, said motor

- having a primary winding adapted to produce primary magnetic fields of two different pole numbers and secondary conductors a portion of which provides a relatively 5 high resistance path for the secondary current with the higher number of primary poles, the other portion remaining inactive; said other portion being so pitched as to become active and form a low resistance path 10 for the secondary current with the lower number of primary poles, and means for developing a motor torque for normal continuous operation of the ship by connecting the primary winding to produce the lower number of poles and for increasing the motor torque for reversing the direction of motion of the ship by connecting the primary winding to produce the higher number 15 of poles.
- 20 5. A system of electric ship propulsion comprising a propeller, an induction motor adapted to drive said propeller, said motor having a primary winding adapted to produce primary magnetic fields of two different pole numbers and two secondary windings one of which is a relatively high resistance squirrel cage winding and the other a low resistance definite winding for the lower number of primary poles which becomes 25 a substantially open-circuited winding for the higher number of primary poles, and means for connecting said primary winding to produce the lower number of poles for normal continuous operation of the ship and for connecting the primary winding to produce the higher number of 30 poles to increase the motor torque for reversing the direction of motion of the ship.
6. A system of electric ship propulsion comprising a propeller, an induction motor 40 adapted to drive said propeller, said motor having a primary winding adapted to produce primary magnetic fields of two different pole numbers and a secondary winding arranged to have one portion yield low effective resistance for the high speed pole number and relatively high effective resistance for the low speed pole number of the primary winding, the other portion being a squirrel cage winding, and means for 45 connecting said primary winding for its high speed pole number for normal continuous operation of the ship and for its low speed pole number for reversing the direction of motion of the ship. 55
7. A system of electric ship propulsion comprising a propeller, a single induction motor adapted to drive said propeller, said motor having a primary winding adapted to produce primary magnetic fields of two different pole numbers and a secondary winding having a portion arranged to be inactive for the high pole number and to be actively included in circuit with the other portion of the secondary winding of the motor for 60 the low pole number of the primary winding, and means for connecting said primary winding for its high speed pole number for normal continuous operation of the ship and for its low speed pole number for reversing 65 the direction of motion of the ship. 70

In witness whereof, I have hereunto set my hand this 7th day of July, 1915.

WILLIAM L. R. EMMET.
